UNITED STATES PATENT OFFICE.

ALLEN J. COUGHENOUR, OF KANSAS CITY, MISSOURI.

EGG-CASE.

1,163,394.

Specification of Letters Patent.

Patented Dec. 7, 1915.

Application filed February 28, 1914. Serial No. 821,659.

To all whom it may concern:

Be it known that I, ALLEN J. COUGHENOUR, a citizen of the United States, and a resident of Kansas City, in the county of Jackson and State of Missouri, have made certain new and useful Improvements in Egg-Cases, of which the following is a specification.

My invention is an improvement in egg cases, and has for its object to provide a case of the character specified, adapted especially for the transportation of eggs, incandescent light bulbs, bottle goods, and like fragile articles by parcels post, express or the like, wherein an outer casing is provided, in which is arranged a carrier containing separate compartments for the individual article, so arranged that the articles may not be in contact with each other, and are held against movement in any direction, and wherein cushioning mechanism is interposed between the carrier and the casing or container, for absorbing the impact of jars received by the container, so that the shock or jar of the impact is not transmitted to the article.

In the drawings: Figure 1 is a section on the line 1—1 of Fig. 3, looking in the direction of the arrows, Fig. 2 is a top plan view of one of the supporting elements for the carrier, Fig. 3 is a top plan view of the case with the cover removed, Fig. 4 is a section on the line 4—4 of Fig. 1, Fig. 5 is a detail section of a modified construction of cushioning device, Figs. 6 and 7 are sections similar to Fig. 4 showing modified connections between the shaft and the carrier, and Fig. 8 is a transverse vertical section of another modification.

The present embodiment of the invention comprises a casing of suitable material and size, the said casing being cylindrical in the present instance, and comprising a tubular body 1 which may be of any desired material, as for instance fiber, a bottom 2, and a cover detachably connected with the body at the opposite end from the bottom.

The bottom 2 is of a size to fit within the end of the body 1 of the casing, and the said bottom is held in place by nails 3 or the like. The detachable cover consists of a disk 4 of the same material as the bottom, and the disk is provided with a facing 5 on its outer

face of metal, and the facing is flanged at its edges, as shown at 6, to engage the periphery of the disk.

An approximately radial rib 7 is formed by bending the material of the facing between the flange and the body, and the said rib is shaped to fit over the upper edge of the body, and to engage outside of the same, as clearly shown in Fig. 1. The cover is held in place by a hasp consisting of two portions 8 and 8^a arranged at approximately a right angle with respect to each other, the portion 8 being superposed on the lining or facing 5 of the cover, and secured thereto by bolts 9 or the like, while the portion 8^a of the hasp is adapted to fit outside of the body, and is provided with a longitudinal slot for receiving a staple 10.

A second hasp 11 is hinged to a plate 12 which is secured to the cover by means of bolts 13, at a point diametrically opposite the hasp 8—8^a, and the hasp 11 is provided with a longitudinal slot for receiving a staple 14 on the body. Padlocks or any other suitable fastening means may be engaged with the staples outside of the hasps to detachably hold the cover in place, and it is obvious that any other desired form of connecting means might be used, instead of the hasps and staples.

A step bearing 15 is secured to the bottom 2 at the center thereof, by means of rivets 16, and the lower end of a standard or shaft 17 is received in the step bearing. A rivet 18 is passed transversely of the lower end of the shaft and the bearing, to hold the shaft in place. The cover is provided with a central opening 19, through which the upper end of the shaft extends, and the said upper end is threaded, as shown at 20 and is engaged by a nut 21 above the cover. The shaft thus assists in locking the cover in place, since the said shaft is secured at one end to the bottom and at the other end to the cover.

A pair of supports is mounted on the shaft, and the carrier for the articles is connected with the support. The carrier for the article is of annular form, and comprises a tube or cylinder 22 of fiber or other suitable material, which is arranged concentric with the shaft 17, and the ends of the tube are connected with the supports be-

fore mentioned. The supports are similar but oppositely arranged. Each of the supports comprises a body 23 and radial arms 24, the said arms being at approximately a 5 right angle with respect to each other, and the body of the support is provided with a cup-shaped or circular depression 25 at its center, and with an opening 26 at the center of the depression.

10 The depressions 25 are of a size to fit within the ends of the tube, and the lowermost support is secured to the tube, by means of rivets 27, which are passed through the web 28 which connects the bottom of the 15 depression with the body of the support, and through the tube, as shown. A series of holders is provided for the articles, each holder consisting of a plate 29 of annular form having at each edge a depending flange 30 and 31 respectively, the former flange 20 being at the inner edge and the latter at the outer edge.

A heavy card board ring 32 is arranged on the arms 24 of the lower support, and the 25 flanges 30 and 31 of the lowermost holder for the article engages the upper face of the said ring, the flange 30 near the inner edge of the ring, and the flange 31 near the outer edge. The articles 33 are held in 30 pockets 34 formed in the plates 29 of the holders, and shaped approximately to fit the article. Each of the pockets is lined with a layer 35 of felt or like material, shaped to fit the pocket, and the holders are 35 preferably formed of some material capable of taking a plastic form, as for instance papier-mâché, paste board or the like.

Each holder is completed by a cover consisting of a plate 36 of annular form and 40 adapted to fit around the tube 22 in the same manner as in the holder just described, and each plate is provided with depending flanges 37 and 38 at its inner and outer edges, and the said flanges engage the plate 45 29 of the holder at the inner and outer edges thereof. Each holder thus consists of the body or holder and the cover, each cover resting upon the body or holder, and each succeeding holder resting upon the cover of 50 the preceding holder.

A ring 39 of felt or other suitable material is arranged within each cover, the said rings 39 engaging and resting upon the article. The shafts 17 pass through the opening 26 55 of the supports, and the supports are cushioned against the bottom and the cover of the container. The openings 26 of the support are of much greater diameter than the shaft, and the lower support is supported by 60 a bracket consisting of a ring or collar 40 which encircles the shaft loosely, and is flanged at each end, as shown at 41.

A pair of arms is connected with the collar, each of the said arms being arched outward intermediate its ends, as shown at 42,

to fit the collar between the flanges, and the arms are connected on opposite sides of the collar by means of rivets 43 or the like. The ends of the arms are bent into approximately semi-circular shape, as shown at 44, 70 and the said ends engage the bottom of the depression 25 of the lowermost support, outside of the opening 26, and they also engage the web 28 which connects the bottom of the depression with the body of the support, as 75 shown in Fig. 4. A similar mechanism is arranged above the upper support, the said mechanism comprising a collar 40, encircling the shaft and having flanges at its ends, together with the arms 42-44, and the 80 rivets 43. The ends 44 of the arms engage the bottom of the depression, and are above the bottom, but occupy precisely the same relative position as the arms and collar at the lowermost support. Were the carrier 85 reversed, so that the cover were at the bottom, the collar and the arms at the top would occupy exactly the same position as the collar and the arms at the bottom.

Coil springs 45 are arranged between each 90 support and the adjacent end of the container or outer casing. The upper spring 45 is arranged between the cover and the arms 42-44, while the lowermost spring is arranged between the lowermost arms 95 42-44 and the step bearing. Preferably the arms 24 of the supports are reinforced by beadings 46, the said beadings being near the edges of the arms, as shown.

It will be evident that the carrier for the 100 articles, that is the supports 23-24, and the holders for the eggs is cushioned with respect to the container or outer casing, in such manner that any shock or jar imparted to the outer casing will be absorbed by the 105 cushion, and will not be transmitted to the articles supported by the carrier. The articles are furthermore cushioned against the 110 holders or carrier, being surrounded by felt on every side. Even were the container reversed, that is arranged wrong end upward, the carrier would yet be cushioned.

To assemble the carrier, that is to pack the articles, they are placed in the respective 115 pockets commencing with the lowermost portion of the lowermost holder, and the carrier is built up, until the topmost cover 36-37-38 is in place. The uppermost support is then placed, after which the uppermost collar and the spring 45 may be arranged. The cover 120 is then placed, after which the nut 21 is threaded onto the upper end of the shaft. It will be noted from an inspection of Fig. 3, that one and one-half dozen of eggs may be 125 placed in each holder, so that four and one-half dozens may be held in a carrier containing three holders.

It will be obvious that by lengthening the 130 container, the capacity of the device as a whole may be greatly increased. The springs

must correspond in strength to the weight of the carrier and the articles to be supported. Preferably the pockets 34 are shaped roughly to fit the articles, and with bottled goods or incandescent globes the said pockets would have slightly different shapes.

In Fig. 5 a modified construction of cushioning device is shown. In this construction, the shaft 17^a is supported at its lower end in a step bearing 15^a which is secured to the bottom 2^a of the outer casing. The support 47, corresponding to the support 23—24 of Fig. 1 differs slightly from the said support, in that the opening at the center of the depression is of larger area than the opening 26. The collar 40^a is provided at each end with flanges 41^a and 48 respectively, the latter flange being of greater extent than the former. The collar encircles the shaft as shown, and the shaft is provided with a longitudinal series of openings 49, through one of which is passed a pin 50 for limiting the movement of the collar. Coil springs 51 are arranged between the flange 48 of the collar and the support, each spring being connected at one end to the flange of the collar and at the other to the support.

In both embodiments of the invention the carrier as a whole may be moved laterally to a limited extent with respect to the shaft 17 or 17^a. In the construction of Fig. 1, this movement is cushioned by the curved portions 44 of the arms 42—44, the said arms being resilient. In the construction of Fig. 5, the springs 51 cushion the lateral movement and also cushion the vertical movement. The collar 40^a is limited in its movement by the pin 50, and when the collar strikes the pin, the springs 51 are placed under tension, thus cushioning the movement of the carrier longitudinally of the shaft. In either construction the carrier may move freely with respect to the container within limits, but movement in any direction is cushioned, so that all jar and shock is absorbed.

In Fig. 6, the collar 52 corresponding to the collar 40 is cushioned against the support 53 corresponding to the support 23—24, by means of a cylinder 54 which is connected to one flange of the collar, and a piston 55 moving in the cylinder, and having its stem 56 connected to the support. A coil spring 57 encircles the stem between the piston and the outer end of the cylinder.

In Fig. 7 links 58 and 59 are connected with the collar 52^a, and with the support 53^a respectively. Each link is provided with a lateral bearing plate 60 at its inner end, through which the other link slides, and a coil spring 61 is arranged between the bearing plates, the spring encircling both links.

In Fig. 8 the shaft is provided with a washer 62, held in place by a pin 63 arranged transversely of the shaft, and a ring

64 provided with inwardly extending resilient fingers 65 is arranged between the support 53^b and the washer. The inner ends of the fingers are provided with arches 66, whose convex surface is adjacent to the shaft, and whose free ends are adjacent to the washer.

The operation of Figs. 6 and 7 will be obvious from the description, as will also be that of Fig. 8. In the three constructions 75 the carrier is cushioned against both lateral and vertical movement. The coil springs 45 may be used with the embodiments shown in Figs. 5 to 8 inclusive, to assist in the cushioning effect.

I claim:—

1. A container for the transportation of fragile articles, comprising a circular casing having a removable cover at one end, a shaft arranged at the axis of the casing and secured thereto at the bottom of the casing, a detachable connection between the shaft and the cover, a carrier of annular form encircling the shaft, the central opening of the carrier being of greater diameter than the shaft, and a yielding connection between the carrier and the shaft, for cushioning movement of the carrier laterally and longitudinally with respect to the shaft.

2. A container for the transportation of fragile articles, comprising a circular casing having a removable cover at one end, a shaft arranged at the axis of the casing and secured thereto at the bottom of the casing, the cover having a central opening through which the shaft is adapted to extend, and the said end of the shaft being threaded, a nut engaging the shaft to clamp the cover in place, a carrier of annular form encircling the shaft, the central opening of the carrier being of greater diameter than the shaft, and a yielding connection between the carrier and the shaft, for cushioning movement of the carrier laterally and longitudinally with respect to the shaft, said connection comprising a collar on the shaft at each end of the carrier, springs arranged between each collar and the carrier, for cushioning the movement of the collar toward the adjacent end of the container and for cushioning movement of the carrier laterally with respect to the shaft.

3. A container for the transportation of fragile articles, comprising a circular casing having a removable cover at one end, a shaft arranged at the axis of the casing and secured thereto at the bottom of the casing, the cover having a central opening through which the shaft is adapted to extend, and the said end of the shaft being threaded, a nut engaging the shaft to clamp the cover in place, a carrier of annular form encircling the shaft, the central opening of the carrier being of greater diameter than the shaft, and a yielding connection between the

carrier and the shaft, for cushioning movement of the carrier laterally and longitudinally with respect to the shaft.

4. A container for the transportation of fragile articles, comprising a substantially cylindrical casing having a detachable cover at one end, a shaft held at the axis of the casing, a carrier for the articles of annular form arranged within the container and encircling the shaft, and cushioning mechanisms arranged between the carrier at each end thereof and the shaft, each of the said mechanisms comprising a collar movable on the shaft, and springs arranged between the collar and the carrier.

5. A container for the transportation of fragile articles, comprising a substantially cylindrical casing having a detachable cover at one end, a shaft held at the axis of the casing, a carrier for the articles of annular form arranged within the container and encircling the shaft, and cushioning mechanism arranged between the carrier at each end thereof and the shaft.

25 6. An egg carrier of annular form and comprising a series of superposed units, each unit comprising a holder and a cover, each of the holders comprising an annular plate having depressed pockets in its upper face for receiving the articles, and having at each side edge a depending flange of approximately the same depth as the pockets and adapted to engage an annular support, each cover being of annular form and having depending flanges for engaging the upper face of the plate of the holder at each side thereof, a lining of cushioning material for the under face of each cover, and a central tube fitting the central openings of

port for the shaft for holding the same in approximately vertical position, a carrier for the articles having a central opening for receiving the shaft, and cushioning mechanism arranged between the shaft and the carrier.

17. A container for the transportation of fragile articles, comprising a central support, a carrier for the articles having a 10 central opening through which the support

extends, and cushioning mechanism arranged between the support and the carrier for cushioning the carrier against lateral and vertical movement with respect to the support.

ALLEN J. COUGHENOUR.
